CLAIM

The ornamental design for an ice chest with attached umbrella holder, as shown and described.

DESCRIPTION

FIG. 1 is a front perspective view of the ice chest with attached umbrella holder showing my new design;

FIG. 2 is a rear perspective view thereof;

FIG. 3 is top view thereof;

FIG. 4 is a bottom view thereof;

FIG. 5 is a front view thereof;

FIG. 6 is a rear view thereof;

FIG. 7 is a left side view thereof; and,

FIG. 8 is a right side view thereof.

The broken lines in the figures illustrate wheels that form no part of the claimed design. The broken lines inside the oval shape in FIG. 5 depict the boundary of the claim and form no part of the claim.
